UNITED STATES PATENT OFFICE.

THEODORE HAUSER, OF CASSOPOLIS, MICHIGAN.

BEDSPRING LOCK.

Application filed July 16, 1923. Serial No. 651,735.

To all whom it may concern:

Be it known that I, THEODORE HAUSER, a citizen of the United States, residing at Cassopolis, in the county of Cass and State of Michigan, have invented certain new and useful Improvements in Bedspring Locks, of which the following is a specification.

The invention relates to bed spring locks, and has for its object to provide means whereby the end convolution of a bed spring may be easily and quickly locked to the cross rails of a bed spring in a manner whereby the convolution of the helical bed spring will be securely held against lateral displacement. The locking arrangement obviates the use of special tools, or tools of any kind for twisting wire, thereby allowing bed springs to be easily and quickly assembled by unskilled labor.

A further object is to provide a helical bed spring mounting comprising tie wires extending transversely through apertures of the cross rails of the bed spring and having offset portions disposed in said apertures, and adjacent apertures in the cross rails, through which the lower convolutions of the helical bed spring extends, said convolutions being interengaged with the tie wires in a manner whereby a downward pressure is applied on the tie wires adjacent the ends of the offset portions of said tie wires, thereby insuring a binding locking engagement of the tie wires and the convolution of the helical spring. The apertures through which the helical spring convolution extends prevents longitudinal displacement of the helical spring in relation to the cross rail, and the offset portion of the tie wires prevents transverse displacement of the helical spring in relation to the cross rail, thereby rigidly holding the helical spring against displacement.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a perspective view of a portion of cross rails of a bed spring, showing the helical spring locking means applied thereto.

Figure 2 is a side view of a conventional form of double helical bed spring.

Figure 3 is a side elevation of a single helical bed spring.

Referring to the drawing, the numeral 1 designates spaced cross rails of a bed spring frame, which rails are formed from metal. Extending transversely through the rails 1, and through apertures 2, therein, are tie wires 3, which wires are provided with segmentally shaped offset portions 4, which are received in the apertures 2. The offset portions 4 are placed in the tie wires 3, in any suitable manner, for instance by crimping and are in the wires 3 when they are placed through the rails 1. The offset portions 4 are in opposed positions to each other, as shown in Figure 1, thereby forming shoulders 5 on opposite sides of the rails 1, and located inwardly in relation to the apertures 2. The helical spring 6, the lower portion of which is shown in Figure 1, for purpose of clearness, is locked to the cross rails 1 and to the tie wires 3 by passing the end 7 of its lower convolution 8 under one of the tie wires 3, and in engagement with one of the shoulders 5, thence through the aperture 9 in the cross rail 1, and thence under the offset portion 4 of the adjacent tie wire 3, after which the end 7 is passed over the tie wire 3 in engagement with the shoulder 5. The operator during this operation guides the end 7 of the convolution 8 while imparting a rotary movement to the coiled spring. As the helical spring is rotated the operator guides the end 7 under the opposite tie wire 3 into engagement with the shoulder 5 of the other offset portion 4, and thence through the aperture 9, after which the end 7 is guided under the adjacent offset portion 4 and over the tie wire 3 into engagement with the adjacent shoulder 5.

It will be seen that the entire operation is accomplished without the use of tools of any kind, and that the locking operation may be quickly accomplished and consequently a bed spring may be assembled with minimum amount of time, and by unskilled labor. During the locking operation the convolution 8 is passed under and over the tie wires 3, at the shoulders 5, and consequently the spring action of the convolution 8 slightly bends or flexes the tie wires 3, which bending, in combination with the constructive action of the convolution 8 in-

sures a positive holding of the convolution and positively prevents lateral displacement of the secured ends of the helical springs 6. By providing the spaced apertures 2 and 9, it is obvious that when the convolution 8 of the helical spring 6 is in engagement with the shoulders 5 of the tie wires 3, the convolution 8 and offset portions 4, which extend through the apertures 2, 9, and 9^a, will engage the walls of said apertures, in a manner whereby transverse lateral movement in relation to the cross rails will be prevented, and any movement in this direction will only tend to more tightly bind the convolutions 8 to the tie wires at the shoulder 5.

Referring to Figure 3 wherein a single helical spring is used, the small convolution 11 thereof is secured in position above the rail 1 in substantially the same manner as that shown in the double helical spring, however in this form the convolution 11 is only passed through the aperture 9, and has a bearing on the upper side of the rail 1, which is sufficient for the small end of a single helical spring, otherwise the operation is substantially the same.

From the above it will be seen that a helical bed spring locking device is provided, which device is simple in construction, and constructed in a manner whereby helical bed springs may be locked simply by imparting a rotation to the helical bed springs and interengaging its end convolution with the cross rails through apertures and with the tie wires, and when interengaged, the helical bed spring will be positively held against lateral displacement. The upper ends of the helical springs may be tied together in any suitable manner.

The invention having been set forth what is claimed as new and useful is:—

1. The combination with a cross rail of a bed spring frame, said cross rail being provided with spaced pairs of apertures, and an end convolution of a helical bed spring extending through the inner apertures of the spaced pairs, of tie wires extending transversely of the rail through the outer apertures of the pairs and interwound with said convolution, by means of which the said convolution is locked to said rail and the tie wires.

2. A helical spring locking device, said device comprising a cross rail having spaced pairs of apertures, tie wires extending trans-

versely of the rail through the outer apertures of the spaced pairs of apertures, the end convolution of the helical spring being interwound with the tie wires and extending through the inner apertures of the spaced pairs of apertures.

3. A helical spring mounting and locking device, said device comprising a cross rail having substantially horizontally aligned spaced pairs of apertures, tie wires extending transversely through the outer apertures of the spaced pairs of apertures, the end convolution of the helical spring being interwound with the tie wires and extending through the inner apertures of the spaced pairs of apertures.

4. A helical spring mounting and locking device, said device comprising a cross rail having spaced pairs of apertures, tie wires extending transversely through the outer apertures of the spaced pairs of apertures, said tie wires being provided with oppositely extending offset portions disposed in the outer apertures of the spaced pairs of apertures, the end convolution of the helical spring being interwound with the tie wires in engagement with the ends of the offset portions of the tie wires and extending through the inner apertures of the spaced pairs of apertures.

5. The combination with a bed spring frame cross rail having spaced pairs of apertures, tie wires extending transversely through the outer apertures of the spaced pairs of apertures, of means for mounting a helical spring on said cross rail, said means comprising offset portions carried by the tie wires and disposed in the outer apertures of the spaced pairs of apertures, the end convolution of the helical spring extending over and under the tie wires, through the inner apertures of the spaced pairs of apertures and in engagement with the ends of the offset portions of the tie wires.

6. The combination with a bed spring frame cross rail, tie wires extending transversely through said rail, a helical spring disposed above the rail, of means for locking the end convolution of the spring to the rail and tie wires, said means comprising the interwinding of the end convolution of the helical spring with the tie wires and through apertures in the rail adjacent the tie wires.

In testimony whereof I affix my signature.

THEODORE HAUSER.
